UNITED STATES PATENT OFFICE.

FREDERICK C. SCHOFIELD, OF LYNCHBURG, VIRGINIA, ASSIGNOR TO THE TOBACCO STEMMING MACHINE COMPANY, OF LYNCHBURG, VIRGINIA, A CORPORATION OF DELAWARE.

TOBACCO-STEMMING MACHINE.

Application filed February 24, 1922. Serial No. 538,842.

To all whom it may concern:

Be it known that I, FREDERICK C. SCHOFIELD, a citizen of the United States, and resident of Lynchburg, in the county of Campbell and State of Virginia, have invented certain new and useful Improvements in Tobacco-Stemming Machines, of which the following is a specification.

This invention relates to a tobacco stemming machine and more particularly to a tobacco stemming machine of the type disclosed in my prior patents No. 1,268,392 of June 4, 1918; and No. 1,286,124 of November 26, 1918; and has special reference to the provision of novel and improved means for feeding or advancing the tobacco leaves and stems in such stemming machines.

In stemming machines of the type referred to, the tobacco leaves are presented, butt ends, to companion gripper bars arranged in and movable with complementary endless chains, the gripper bars being operative to close upon and clamp the butt ends of the leaves and convey or carry the same forward between rotatable stemming elements, the latter functioning to strip the lamina of the leaves from the stems during movement of the leaves therebetween. In stemming machines of this type a quantity of leaves untied from a "hand" is spread over a table or similar support and all the leaves are simultaneously fed, butt ends, to the gripper bars to be clamped thereby. In the feeding of the leaves to the bars it is highly desirable, if not indeed essential, that the butt ends of all the leaves be "taken hold of" by the gripper bars so that all the leaves on the table be clasped by the bars to be fed forward; that, furthermore, all the butt ends of the leaves be gripped or clamped with security so as to minimize what is known as "drops" during the stemming operation and that, moreover, the leaves be gripped at their true butt ends and not in regions spaced from such ends so that most of the leaf be subjected to the stemming action of the stemming elements.

To accomplish these desired ends a number of methods and means have been employed but with indifferent success. A common method consists in providing means for alining the butt ends of the leaves and in positioning the leaves by hand with the butt ends up against the alining means, the leaves being so positioned and alined as to have the

butt ends intersect the path of movement of the gripper bars. I have found a number of disadvantages inherent in the employment of this type of means, depending upon the specific type of mechanism utilized. Where, for example, movable gate members are employed as the butt alining means, the member being arranged in the path of movement of the bars and movable out of the way by the passage of the bars, I have found that the alining of the butts is not accomplished with that degree of exactitude desirable, the movable gate means being not sufficiently stable and rigid for this purpose, and that there is a tendency of too much "butt" being grasped by the bars, this being the result of positioning the alining means beyond or in advance of the zone or region of closing of the bars. Where rigid alining means not in the path of movement of the bars is used, exact results have been found relatively difficult of attainment. To eliminate these disadvantages and operating defects in prior stemming machines of this type and to provide a stemming machine in which the leaves may be fed or advanced in position to be clamped by the gripper bars so that all the leaves are clamped and are clamped securely with a predetermined amount of butt ends of the leaves so clamped is a prime desideratum of my present invention.

After the butt ends of the leaves are gripped by the bars in stemming machines of the type referred to, the leaves, as heretofore mentioned, are fed through main stemming elements, the latter being active for removing the lamina or blade from the leaf stem by a wiping action. After main stemming action it is desirable to salvage or reclaim the lamina still adhering to the stem such as those portions on the butt ends which have been shielded from the main stemming elements by the bars and those portions which may have escaped the action of the stemming elements in other ways; and to this end it is desirable to free the stems from the bars and feed the same with the adhering lamina portions through secondary stemming elements. To accomplish this, secondary stemming elements are provided and located at the end of the endless chain carriers and gripper bars and the parts are so arranged that the stems freed upon separation of the bars are forwarded for stem-

ming to the stemming elements. To accurately feed and forward all the stems held by the bars to the stemming means, which is spaced some distance from the separating bars, is a matter, however, which has not been found free from difficulty. If the bars have engaged, for example, the extreme butt ends of the stems, these butt ends when released or freed by the bars are at a distance 10 from the stemming devices or forwarding devices associated therewith when they are so freed and difficulty has been encountered in directing the freed butt ends through the secondary stemming means. To improve the 15 means for feeding these released stems to and through the secondary stemming devices is a further prime desideratum of my present invention.

The principal objects of my present invention may be said to include, besides the provision of a stemming machine of the type referred to having novel and improved means for feeding and advancing the tobacco leaves and stems; the provision of means for 20 permitting the definite positioning of the leaves with all their butt ends accurately alined, associated with means for feeding the leaves from such position into a predetermined position to be grasped or clamped 25 by the closing complemental gripper bars; the provision of a feeding means of this nature which is operative to positively grip the leaves and advance the same into said predetermined position; the provision of 30 apparatus of this nature in which the alining means is out of the path of movement of the bars and arranged in such a manner that the butt ends of the leaves are fed for gripping purposes after being alined and 35 are fed to permit the gripping of the desired portion of the butt ends of the leaves; the further provision of feeding means capable of releasing hold of the tobacco leaves when the same are gripped by the bars and 40 drawn on thereby; the still further provision of means for directly feeding the stems from the gripper bars to the secondary stemming devices with such means arranged 45 to grip the stems close to the butt ends 50 thereof following the release of the same by the bars and the further provision of apparatus of this nature simple in construction and capable of efficient operation and control.

To the accomplishment of the foregoing and such other objects as may hereinafter appear, my invention consists in the elements and their relation one to the other, as hereinafter particularly described and 55 sought to be defined in the claims, reference being had to the accompanying drawings which show a preferred embodiment of my invention and in which:

Figure 1 is an elevational view of my 60 stemming machine showing the means for

feeding and advancing the leaves and stems, parts of the stemming machine being broken away and other parts shown in section,

Figures 2 and 3 are fragmentary elevational views of the means for feeding the 70 leaves and advancing the same to the gripper bars showing the same in successive stages of operation,

Figure 4 is a fragmentary elevational view with parts in cross section of the means 75 for feeding the stems to the secondary stemming elements, the parts being here shown in a successive stage of operation as compared with Figure 1, and

Figure 5 is a plan view of the stemming 80 machine with the parts in position as shown in Figure 1.

Referring now in detail to the drawings, the stemming machine of my present invention is of the type as disclosed in my prior 85 patents above mentioned, in which are provided complemental sets of companion endless chains 10 and 11, the endless chains 10 comprising the upper carrier chains upon which are arranged in spaced relation 90 the clamping bars 12, the set of chains 11 comprising the lower carrier chains upon which are spacedly arranged the companion gripper bars 13. The endless carrier chains 10 are movable over sets of 95 spaced sprocket wheels 14 and 15 respectively, the sprocket wheels 14 being pinned to a shaft 16 journalled in the framework 17 at one end of the machine, the sprocket 100 wheels 15 being similarly pinned to a shaft 18 journalled in the framework 17 of the machine at the other end of the same. In a similar manner the lower carrier chains 11 are trained and movable over the sets of spaced sprocket wheels 19 and 20, the 105 sprocket wheels 19 being fixed to a shaft 21 journalled in the framework of the machine, the said shaft being arranged in the plane of the shaft 16 and the sprocket wheels 20 being fixed to a shaft 22 journalled in the 110 framework of the machine, the said latter shaft being arranged in the plane of the shaft 18. For suitably tensioning the sprocket chains 10 and 11 the shafts 16 and 21 may be slidably mounted in the 115 framework 17 of the machine and to this end the said shafts are journalled in blocks 23 and 24 respectively, the said blocks being movable in guideways 25 and 26 respectively, adjusting or set screw devices 27 and 28 respectively being employed for adjusting and locking the journalled blocks 23 and 24 in desired position. The endless carrier chains 10 and 11 are movable, as shown by the arrows in Figure 1 of the drawings, so 120 that the adjacent bights of the chains are movable in the same direction, the construction and movement being such that the complemental or companion gripper bars 12 and 13 are 125 movable in the sets of sprocket wheels 14

and 19 meet and close for clamping or gripping therebetween the butt ends of the tobacco leaves fed or advanced thereto as is well known in this type of device, the leaves 5 so clamped by the bars being then drawn through stemming elements (not shown) such as disclosed in my prior patents, the removal of the lamina or blades from the stems of the leaves being effected during 10 movement of the leaves through the stemming elements.

As heretofore mentioned, a principal object of my present invention comprehends the provision of a construction in which the 15 tobacco leaves may be accurately fed with their butt ends in properly alined positions to the movable gripper or clamping bars 12 and 13 so that the clamping of all the leaves fed to the bars will be assured and so 20 that such clamping takes place not only with sufficient security to draw the leaves through the stemming elements without the occurrence of "drops" but at predetermined portions of the butt ends of the leaves to 25 the end of preventing or minimizing too large a portion of the stems being gripped between the bars and shielded from the main stemming elements. To this end my 30 invention comprehends an arrangement in which the butt ends of the leaves may be alined in a definite manner prior to feeding the leaves to a position intersecting the path of movement of the gripper bars, then after the leaves are so alined to feed the 35 same into the desired position in a positive manner and so that predetermined portions of the butt ends of the leaves will be presented for clamping action to the bars. Referring to the drawings which show one 40 exemplification of my invention, I provide the central table T upon which are spread a plurality of leaves L and arranged between the said table T and the endless chain carriers 10 and 11 I provide a butt end alining 45 means A, the leaves L positioned by hand on the table T being spread apart by the operator and moved into definite position- 50 ing with the butt ends of the leaves up against the alining means A and for feeding the leaves from such positions to a position to be gripped by the gripper bars 12 and 13 I provide the feeding means F.

The table T of my invention is prefer- 55 ably made to comprise an oscillatable sup- port for a purpose as will appear presently, the said table being oscillatably mounted on the side tables 29 and 30 by means of the trunnions 31 and 32. The butt end alining means A in the present form of my inven- 60 tion comprises preferably an oscillatable gauge board or gate 33 journaled by means of the trunnions 34 and 35 in suitable bear- 65 ings 36 and 37 forming part of the frame- work of the machine, the said gate or gauge board being movable from a vertical posi-

tion as shown in Figure 1 to a position in- 70 clined thereto, as shown in Figures 2 and 3 of the drawings, the gauge board acting in the former position as a butt alining means and functioning in the latter position 75 as a guide or slide to permit forward or advance movement of the leaves L as will become clearer hereinafter. The butt alining means A may be moved into either of its two positions in any desired manner and 80 in the preferred construction the said butt alining means is preferably moved by the oscillation of the table T. To this end the said table T is provided with the end plates 88 and 39 secured to the sides of the table 85 T in any preferred manner, the said plates 38 and 39 being provided with lugs 40 and 41 receiving the set screws 42 and 43, the bottoms of the said set screws being intend- 90 ed for engaging the finger pieces 44 and 45 85 fixedly attached to the trunnions 34 and 35 of the butt alining means A. With this con- 95 struction it will be apparent that upon downward movement of the table T the set screws 43 and 43 will positively engage 90 the fingers 44 and 45 and move the butt alining means to the vertical position as shown in Figure 1 of the drawings; and with this construction it will be further ap- 100 parent that when the butt alining means A 95 is so moved to vertical position the gate or gauge board 33 will assume a definite and rigid position capable of definitely alin- 105 ing the butt ends of the leaves L. For mov- 100 ing the alining means to the inclined po- 110 sition as shown in Figures 2 and 3 of the drawings, I preferably provide the tension springs 46 and 47 each anchored at one end to the table T as at 48 and 49 and at the other end to the butt alining means A be- 115 neath the axis of oscillation thereof, as at 50 and 51, the construction being such that upon upward or ascending movement of the table T and upon release of the fingers 44 and 45 the tension springs 46 and 47 will 110 move the gate or gauge board 33 to the in- 115 clined position shown in Figures 2 and 3 of the drawings.

For accurately feeding the alined leaves L into position to be clamped by the gripper bars 12 and 13 the feeding means F of 120 my construction comprises, generically, a supporting roller 52 preferably journaled in the end plates 38 and 39 of the table T and a cooperating drum segment 53 fixed to a 125 shaft 54 journaled in the framework of the machine, the said shaft being intended to be positively driven to effect the rotation of the segment 53 in the direction shown by the arrow in Figure 1 of the drawings. The 125 supporting roller 52 is preferably provided with a resilient contact surface such as rubber and is so relatively disposed to the drum segment 53 as to permit a yielding yet posi- 130 tive gripping or clamping of the leaves L for

feeding the same forward. The provision of a drum segment 53 as shown permits the insertion or the positioning of the leaves L into alined positions without interference and after the leaves are so positioned the drum segment movable thereover and into cooperation with the resilient roller 52 grasps the leaves in a positive manner for feeding the same forward.

10 For the purpose of preventing the drum segment 53 from coming into contact with the tobacco leaves prior to the point of gripping the same, this to the end of preventing dragging of the tobacco out of line or pushing 15 part of the leaves ahead, the roller 52 is preferably given a motion to and from the drum segment 53 and it is to this end that the table T upon which the roller 52 is journalled is mounted for oscillatable motion. To the end 20 of effecting the up and down movement of the roller 52 and the oscillation of the table T I provide the cam 55 fixed to the shaft 54, the said cam being provided with the cam track 56 with which cooperates the cam follower 57, the latter being mounted at the end 25 of a cam slide 58, the said slide being provided with a toe portion 59 at its bottom portion for receiving an adjusting or set screw device 60, the shank of the set screw device 30 60 being adapted to engage a lug 61 which may be formed integral with the side plate 38. These parts are so constructed, as will be evident from a consideration, for example, of Figures 1 to 3 of the drawings, that 35 upon rotation of the drum segment 53 into gripping contact with the roller 52 the cam slide 58 moves the table T upwardly, the cam follower 57 riding over the cam track 56. The leaves are by this means positively 40 engaged between the roller 52 and drum segment 53, these parts furthermore having a tendency to spread the butt ends of the leaves apart without moving the leaves longitudinally one relative to the other, all the 45 butt ends being thus conditioned for proper gripping action by the clamping bars. The adjusting device or set screw 60 is provided to the end of adjusting the yielding clamping 50 between the roller 52 and the drum segment 53. The drum segment 53, moreover, is preferably made of the proper length of surface or degree of a circle to advance the tobacco to a point where the gripper bars 12 and 13 can take the proper hold of the 55 tobacco stems and then pass on, allowing the bars to drag or draw the tobacco without retarding interference. Upon comparison of Figures 1 to 3 of the drawings it will be seen that prior to the engagement of the drum segment 53 with the leaves L the roller 52 is in its descended position with the butt alining means in vertical position (Figure 1) and as the drum segment 53 moves into engagement with the leaves L the roller 52 is moved to ascended position while

simultaneously the butt alining means A is moved to inclined position (Figure 2); the said butt alining means now functioning or serving as a slide or guide for the butt ends of the leaves, the leaves being then advanced into position to be gripped by the gripper bars 12 and 13, the arrangement of the parts being such that all the butt ends and only the butt ends are presented for clamping action by the bars, this being clearly shown in Figure 3 of the drawings, the drum segment 53 moving out of contact with the roller 52, as shown in Figure 3, after the gripping of the leaves by the bars has been effected. The table is then moved to descended position ready for the next spread of tobacco leaves thereon.

For the purpose of driving or operating the cam 55 and the drum segment 53 I provide the gear wheel 62 fixed to the cam shaft 54 and meshing with this gear wheel I provide the pinion 63, the latter being fixed to a shaft 64 carrying the bevel gear 65, the latter meshing with a bevel pinion 66 fixed to a shaft 67 journalled as at 68 in the framework of the machine. For the purpose of predetermining the position of the drum segment 53 with respect to the movable gripper bars 12 and 13 and for advancing or retarding the former with respect to the latter 95 for the purpose of giving the bars a greater or lesser hold on the tobacco, as desired, I provide means for relatively adjusting the position of the drum segment 53 with respect to the movement of the gripper bars 12 and 13. To this end I provide the drive shaft 69 which has a motion synchronized with the motion of the carrier chains 10 and 11, the said drive shaft 69 being connected to the shaft 67 by means of a coupling 70, the latter pinned to the shaft 69, as at 71 and connected to the shaft 67 by means of a releasable screw or bolt 72. With the provision of this means it will be seen that the bolt or similar device 72 may be released 100 and that the shaft 67 may be rotated relatively to the shaft 69 for advancing or retarding the position of the drum segment 53 relative to the position of the gripper bars 12 and 13.

As heretofore mentioned, a further principal object of my present invention comprehends the provision of means for accurately feeding the stripped stems from between the gripper bars 12 and 13 to a secondary or supplemental stemming device for removing the lamina adhering to the leaves as, for example, such lamina at the butt ends of the leaves which have been shielded from the stemming action of the main stemming devices and such lamina which have escaped the action of the main stemming apparatus. The secondary stemming devices are arranged at the advance end of the machine, and referring to Figures 105 110 115 120 125 130

- 1, 4 and 5 of the drawings, I show the provision of a set of supplementary stemming rolls 73 and 74 of the usual type having, for example, card clothing surfaces, the 5 said stemming rolls being rotatable in opposite directions as shown by the arrows in the figures, the stemming rolls receiving motion in any suitable manner as from a belt 75 movable over a pulley 76 fixed to the 10 shaft of one of the stemming elements, the stemming rolls being housed by the chute cover 77. For forwarding the stems S of the leaves L from the gripper bars 12 and 13 to the stemming rolls 73 and 74 I provide 15 the forwarding rolls 78 and 79, these forwarding rolls being actuated by any suitable means as by means of a sprocket chain 80 trained over sprockets 81 and 82 arranged respectively on the sprocket shaft 18 and the 20 shaft of the roll 78. Upon separation of the gripper bars 12 and 13 as they round the sets of sprockets 15 and 20 the stems S are fed to the forwarding rolls 78 and 79, the latter moving at a peripheral speed equal to the 25 rectilinear speed of the gripper bars, the forwarding rolls in turn feeding the leaves to the stemming rolls 73 and 74, the latter being rotated at a speed much greater than the advancing speed of the forwarding rolls 30 78 and 79, stemming of the adhering lamina taking place in this manner, as clearly appears from a consideration of Figure 4 of the drawings, the tobacco flakes removed from the stems S falling into the chute 77. 35 The feeding of the stems S from the gripper bars 12 and 13 to the secondary stemming devices has been found to be a matter attended with considerable difficulty, especially where a plurality of stems are intended to be forwarded with precision through the 40 forwarding rolls. The forwarding rolls are, of necessity, situated at a distance from the separating gripper bars and where the butt ends of the stems S only have been gripped 45 by the bars, the butt ends when released by the gripper bars are at a substantial distance from the forwarding rolls 78 and 79 and directing of these free ends between the forwarding rolls is attended with difficulty. 50 To the end of improving the means for feeding the stems to the forwarding rolls 78 and 79 my present invention comprehends the provision of an apparatus by which the stems S may be taken hold of close to or 55 substantially close to the butt ends when the latter are freed by the separation of the gripper bars, the leaves so taken hold of being capable of easier feeding into the forwarding rolls 78 and 79. To these ends my 60 present invention comprehends the provision of means rotatable about the axes of the sets of sprocket wheels 15 and 20, such means being constructed so as not to interfere with the action of the gripper bars and being arranged to follow the gripper bars and clamp 65 the stems after the latter are released by the gripper bars. Accordingly, fixed to the shafts 18 and 22 I provide the drum segments 83 and 84 movable in opposite directions as indicated by the arrows in Figures 70 1 and 4 of the drawings, the said drum segments being so arranged and disposed relatively to the movement of the gripper bars 12 and 13 as to clamp the stems near their butt ends as clearly shown in Figure 1 of the drawings, the stems so clamped being advanced to and between the forwarding rolls 78 and 79, as clearly appears from a 75 consideration of Figure 4 of the drawings. The operation of my stemming machine 80 and the feeding means therefor will, in the main, be apparent from the above detailed description thereof. It will be apparent that when the leaves L are untied from a "hand" they may be spread over the table T 85 by the operator, the operator pushing the leaves with their butt ends into alined position against the gauge board 33, the latter being rigidly positioned to effect proper alining of all the leaves. After the leaves 90 are so alined they are positively and resiliently gripped between the supporting roller 52 and the drum segment 53, these parts being so constructed and operated as to prevent any relative longitudinal movement of 95 the leaves and as to prevent the pushing of part of the leaves ahead, the leaves being by this means gripped in a positive and definite manner for advancing the same into a predetermined definite position relative to the 100 movable gripper bars 12 and 13, the latter securely clamping the butt ends only of the leaves for drawing the same on for stemming activity. After the leaves have been stemmed the stems S are forwarded in an 105 efficient manner by means of the drum segments 83 and 84 to the secondary stemming rolls 73 and 74, the latter functioning for removing the lamina still adhering to the 110 stems. While I have shown my device in the preferred form, it will be obvious that many changes and modifications may be made in the structure disclosed without departing from the spirit of the invention, defined in 115 the following claims. I claim: 1. In a stemming machine, in combination with movable complemental gripper devices for clamping therebetween the tobacco leaves and conveying the same through stemming elements, a support for receiving the leaves to be stemmed and continuously operable mechanism effective intermittently on the leaves for feeding the same from said support into 120 position to be clamped by said gripper devices. 2. In a stemming machine, in combination with movable complemental gripper devices for clamping therebetween the tobacco leaves 125 130

and conveying the same through stemming elements, a support for receiving the leaves to be stemmed, means associated with said support for positioning the leaves on the support with their stem ends aligned and mechanism operative only after the leaves are so positioned for feeding the same from said support into position to be clamped by said gripper devices.

10. 3. In a stemming machine, in combination with movable complementary gripper devices for clamping therebetween the tobacco leaves and conveying the same through stemming elements, a support for receiving the leaves to be stemmed and mechanism for feeding the leaves from said support into position to be clamped by said gripper devices; the said mechanism comprising means active intermittently for engaging the leaves on opposite sides thereof and for positively feeding the same forward.

4. In a stemming machine, in combination with movable complementary gripper devices for clamping therebetween the tobacco leaves and conveying the same through stemming elements, a support for receiving the leaves to be stemmed and mechanism intermittently operative on leaves received by said support for advancing the leaves from the support into position to be clamped by said gripper devices.

5. In a stemming machine, in combination with movable complementary gripper devices having a predetermined path of movement and operative for clamping therebetween the tobacco leaves and conveying the same through stemming elements, a support for receiving the leaves to be stemmed, means positioned between said support and the path of movement of said gripper devices for positioning the leaves with their butt ends aligned and mechanism operative only after the leaves are so positioned for advancing the leaves so positioned from the support into position to be clamped by the gripper devices.

6. In a stemming machine, in combination with movable complementary gripper devices for clamping therebetween the tobacco leaves and conveying the same through stemming elements, a support for receiving the leaves to be stemmed and mechanism for feeding the leaves from said support into position to be clamped by said gripper devices, the said mechanism including a drum segment.

7. In a stemming machine, in combination with movable complementary gripper devices for clamping therebetween the tobacco leaves and conveying the same through stemming elements, a support for receiving the leaves to be stemmed and mechanism for feeding the leaves from said support into position to be clamped by said gripper devices; the said mechanism including a sup-

porting roller and a rotatable drum segment cooperating therewith, the roller and segment cooperating to grip the leaves therebetween and feed the same forward positively.

8. In a machine of the class described, in combination, means for feeding leaves forwardly for stemming the same, the said means including a feeding drum segment.

9. In a machine of the class described, in combination, means for feeding leaves forwardly for stemming the same, the said means including rotatable members positioned to grip therebetween the tobacco leaves and feed the same, one of said members comprising a drum segment.

10. In a machine of the class described, in combination, means for feeding leaves forwardly for stemming the same, the said means including rotatable members positioned to grip therebetween the tobacco leaves and feed the same, one of said members comprising a supporting roller and the other of said members comprising a drum segment intermittently cooperating therewith.

11. In a machine of the class described, in combination, means for feeding leaves forwardly for stemming the same, the said means including oppositely rotatable drum segments operative for gripping the leaf stems therebetween and advancing the same.

12. In a tobacco stemming machine, in combination with endless complementary carriers and companion gripper bars arranged thereon; the said gripper bars being movable into and out of gripping relation to clamp leaf stems therebetween and feed the same forwardly and means for gripping and feeding the stems upon release of the stems by the gripper bars, the said means including drum segments.

13. In a tobacco stemming machine, in combination, complementary endless carriers movable about axes arranged in planes spaced longitudinally of the machine, companion gripper bars disposed on said endless carriers and movable into and out of gripping relation for clamping and feeding the stems and drum segments arranged for rotation about the axes in one of said planes, the construction being such that the drum segments follow the moving bars and cooperate for gripping and feeding the stems upon separation of the bars.

14. In a tobacco stemming machine, in combination, a stemming device, complementary endless carriers movable about axes arranged in planes spaced longitudinally of the machine, companion gripper bars disposed on said endless carriers and movable into and out of gripping relation for clamping and feeding the stems to said stemming device and drum segments arranged for rotation about the axes in one of said planes,

the construction being such that the drum segments follow the moving bars and cooperate for gripping and feeding the stems to said stemming device upon separation of the bars.

15. In a machine of the class described, means for feeding leaves to be stemmed, the said means comprising a rotatable supporting member, a rotating drum segment movable thereover and into gripping contact therewith and means for moving the member to and from the drum segment.

16. In a machine of the class described, a support for receiving leaves to be stemmed, means for feeding the leaves from the said support, the said means comprising a rotatable supporting member journaled in the support, a rotating drum segment movable thereover and into gripping contact therewith and means for moving the support and its member to and from the drum segment.

17. In a machine of the class described, means for feeding leaves to be stemmed, the said means comprising a rotatable supporting member, a rotating drum segment movable thereover and into gripping contact therewith, means for moving the member to and from the drum segment and means for adjusting or regulating the gripping contact between the said member and drum segment.

18. In a tobacco stemming machine, means for receiving the leaves to be stemmed, the said means including a movable element for alining the butt ends of the leaf stems, mechanism for feeding the leaves forwardly, the said mechanism including a rotatable supporting member and a drum segment movable into and out of cooperative relation therewith and instrumentalities for effecting movement of the said elements.

19. In a machine of the class described, a movable gate for alining the ends of the leaves to be stemmed, means for feeding the leaves, the said means comprising a rotatable supporting member, a rotating drum segment movable thereover and into gripping contact therewith and means for moving the member to and from the drum segment, the construction being such that movement of said member effects movement of said alining gate.

20. In a machine of the class described, a support for receiving leaves to be stemmed, a movable stem alining means associated therewith, means for feeding the leaves from said support, the said means comprising a rotatable supporting member journaled in the said support, a rotatable drum segment movable thereover and means for moving the support and member to and from

the drum segment, the construction being such that movement of said support and member effects movement of the stem alining means.

21. In a machine of the class described, in combination, means for feeding leaves forwardly for stemming the same, the said means including a feeding drum segment and mechanism for rotating the drum segment, the said mechanism including means for advancing or retarding the drum segment relative to a driving means.

22. In a stemming machine, in combination with movable complemental gripper devices for clamping therebetween the stem ends of tobacco leaves and conveying the same through stemming elements, mechanism including a rotatable drum segment for advancing the leaves into position to be clamped by the gripper bars, mechanism for moving the devices and rotating the segment and means for advancing or retarding the gripper devices and segment one relative to the other.

23. In a tobacco stemming machine, an oscillatable gate member arranged for oscillation from a vertical position to a position inclined thereto, the gate member being active as a gauge and a slide in the vertical and inclined positions respectively, an oscillatable support, a roller in said support, means connecting said support with said gate member whereby oscillation of said support will effect oscillation of said gate member and means for oscillating said support.

24. In a machine of the class described, in combination, means for feeding leaves forwardly for stemming the same, the said means including rotatable members positioned to grip therebetween the stems of the leaves and feed the same, one of said members comprising a supporting roller and the other of said members comprising a drum segment intermittently cooperating therewith and means for adjusting the position of the roller relative to the drum segment.

25. In a machine of the class described, in combination with movable complemental gripper devices, means for feeding leaves to be stemmed to said gripper devices, the said means comprising a rotatable supporting member, a rotating drum segment movable thereover and into gripping contact therewith and means for moving the member to and from the drum segment.

Signed at Lynchburg, in the county of Campbell and State of Virginia this 17th day of February A. D. 1922.

FREDERICK C. SCHOFIELD.
